UNITED STATES PATENT OFFICE.

GEORGE L. BADGER, OF QUINCY, MASSACHUSETTS.

PNEUMATIC IMPACT-TOOL.

No. 893,296.

Specification of Letters Patent.

Patented July 14, 1908.

Application filed January 8, 1906. Serial No. 295,083.

To all whom it may concern:

Be it known that I, GEORGE L. BADGER, a citizen of the United States, residing at Quincy, in the county of Norfolk, State of Massachusetts, have invented a certain new and useful Improvement in Pneumatic Impact-Tools, of which the following is a specification, reference being had therein to the accompanying drawings.

- 10 This invention relates to improvements in pneumatic impact-tools, and more particularly to that class in which it is essential to rotate the working-tool with relation to the work as when drilling holes in stone.
- 15 The principal objects of the invention are to provide durable and cheaply constructed means to hold the working-tool in alinement with the piston, to limit the rearward movement of the working-tool, to rotate the 20 same, and to permit a longitudinal movement of the working-tool with relation to the cylinder when the working-tool is rotated.

In pneumatic impact-tools of the type in which the piston strikes directly on the 25 working-tool, in order to obtain the best results, it is necessary that the working-tool shall be in its proper longitudinal position with relation to the cylinder at the moment of impact. It is the usual practice to form a 30 round shank on the end of the working-tool which fits a hole in the end of the cylinder; the shank being smaller than the body of the working-tool, thus forming a shoulder which serves to limit its rearward movement. This 35 is objectionable because of the expense of forming and maintaining the round shanks of the working-tools all of uniform diameter and length, as they should be to obtain the best results. The tools wear rapidly and become 40 too short for this use, and in order to utilize the steels for other purposes, the shank has to be cut off. A large proportion of the steels break at the shoulder when in use, resulting in a further loss of material and the cost of 45 forming new shanks and shortened life of the working-tool. The hole in the cylinder which receives the shanks is worn large and new tools do not fit properly, and the wear of the shoulder on the steels and the end of the hole 50 causes longitudinal displacement of the steel. In some tools of this type a bushing or socket is employed having a bore of two diameters, the smaller bore being at the rear, thereby forming a shoulder against which the end of 55 the working-tool bears to limit the rearward movement. The end of the piston is made

small enough to pass through the small bore of the bushing and strike the end of the working-tool. This construction is suitable for light work, such as lettering and carving, but for heavy work, the end of the piston is too small and breaks when the standard sizes of steel are employed.

In my application Serial No. 244,765, filed February 8, 1905, I have shown a striker or block interposed between the working-tool and the piston adapted to receive and transmit the blow of the piston and to limit the rearward movement of the working-tool. This construction allows for the employment 65 of standard steels without any reforming for the shanks whatever. On account of the variation in the sizes of the steels, the chuck cannot be made to fit the steels closely, and as it wears larger in use, it is difficult to maintain the working-tool in alinement with the piston. This is also the case when a round shank and shoulder are used, as the hole for the shank wears and becomes too large, and when the working-tool is not in alinement 70 with the piston, the piston does not strike the end of the working-tool squarely, thus lessening the force of the blow and tending to drive the working-tool to one side and bind the same in the hole of the cylinder or bushing.

I have found that in some cases better results are obtained when the piston strikes the working-tool directly, and by providing means for holding the rear end of the working-tool in alinement with the piston, and also limiting its rearward movement independently of the hole in the bushing or socket, the objectionable features above mentioned are practically overcome.

The ends or heads of the working-tools are fitted to the holder at a very slight expense, the heads being of practically the same form used for hand drilling; there is no waste in using the steels for other purposes; the steels being of full size and without shoulders, there is no breakage of shanks; a close fit in the socket is not required, and the wear of the hole does not interfere with the proper operation of the tool, as the piston always strike squarely on the end of the steel; the bearing surfaces limiting the rearward movement are so large that the wear is very slight and all the steels used are always maintained at the proper distance for 105 the piston to strike the most effective blow. When tools of this class are employed for 110

heavy work, it is essential in order to obtain the best results that the working-tool shall be free to move longitudinally with relation to the cylinder in order that the cylinder 5 may be returned to or maintained in the proper position after the working-tool is struck by the piston, as on account of the vibration of the tool there is a tendency for the cylinder to move rearward or away from the working-tool.

10 There is always a tendency for the working-tool to bind in the hole being drilled, especially when using single or flat bits, and when the working-tool is rotated by means 15 of a socket or chuck adapted to engage a non-circular shank thereon, the friction is often great enough to prevent the shank from sliding in the socket to allow the cylinder to move forward to the proper position 20 relative to the rear end of the working-tool. I overcome this difficulty by providing means whereby the working-tool is free to move longitudinally with relation to the cylinder without sliding in the socket or chuck.

25 With the aforesaid objects in view my invention consists in certain features of construction and combination of parts, as will be hereinafter described and pointed out in the claims.

30 In the accompanying drawings,—Figure 1 is an elevation partly in section of a tool embodying my invention, showing the lower portion broken away. Fig. 2 is a modification showing other means to hold the socket 35 or chuck in position. Fig. 3 is a modification showing the stop for the working-tool integral with the socket.

Referring to the drawings,—the cylinder is denoted by 1.

40 2 is the forward end of the piston; 3 is the socket or chuck and 4 is a stop-ring. A bushing 5 is adapted to retain the stop-ring and socket in assembled position in the cylinder. A handle 6 is secured to the socket 45 by means of which the latter is rotated to rotate the working-tool 7.

In the modification shown in Fig. 2, a spring-clip 8 is adapted to retain the socket in the cylinder.

50 I have not deemed it necessary to show and describe in detail the construction of the cylinder, valve and piston, as the construction of the same does not form an essential part of the present invention which is equally 55 applicable to the pneumatic tool shown in my application hereinabove referred to or other types of pneumatic tools.

The shank of the working-tool 7 is of non-circular cross-section except at the rear end 60 which is of circular cross-section and tapered to fit the tapered hole in the stop-ring 4 so that it will project through the latter a short distance as shown. The stop-ring is made a working fit in the counterbore of the cylinder, and its rearward movement is limited by

the shoulder 9. In the construction shown in Fig. 1, the socket 3 is provided with a flange 10 which fits the counterbore of the cylinder loosely, and the smaller diameter is a working fit in the bore of the bushing 5. 70 The opening through the socket is of non-circular cross-section adapted to receive the shank of the working-tool so that the latter will slide freely therein. The outside diameter of the bushing 5 is made so that it is a 75 tight driving fit in the counterbore of the cylinder.

The distance between the rear end of the bushing 5 and the shoulder 9 of the cylinder is enough greater than the thickness of the 80 stop-ring and the flange 10 of the socket to allow the stop-ring to move out of the path of the piston and prevent the end of the piston from striking the stop-ring when the working-tool is not in its proper position, which 85 often occurs when starting holes on account of the jumping of the tool due to the carelessness of the operator. This permits the shoulder 12 on the piston to strike the shoulder 13 of the cylinder. It will be understood 90 that when the tool is used in a vertical position the stop-ring will move away from the shoulder 9 by gravity when the working-tool is removed.

In order to accomplish the best results, it 95 is necessary to provide for a considerable range of movement of the stop-ring. The tools used for certain purposes such as drilling strike such a powerful blow that in order to prevent injury to the tool it is necessary to 100 allow considerable space in which the motive fluid may cushion the blow of the piston when the working-tool is displaced and as before stated the stop-ring requires a sufficient space to move out of the path of the 105 piston.

As shown in the drawings, when the working-tool is in its normal position, there is a space 11 between the stop-ring and the socket. The handle 6 is secured to the 110 socket in such position as to allow a longitudinal movement of the latter with relation to the cylinder, so that if the shank of the working-tool binds in the socket when the working-tool is somewhat forward of its proper 115 position, the cylinder can move forward by the bushing 5 sliding on the socket 3 to bring the working-tool into proper working position. This feature is of great importance for portable pneumatic hand tools for drilling 120 holes in rock, as it relieves the socket and cooperating parts from a great deal of the strain and wear that they would otherwise receive. It also allows the tool to do more rapid work.

When the shank of the working-tool is 125 gripped tightly by the socket, as is the case when the cutting-bit binds in the hole, and the operator tries to turn it by pressing on the handle, the blow of the piston on the end 130

of the working-tool tends to carry the latter forward, but since the other end is in contact with the rock, the cylinder is moved rearwardly a short distance; in order to return the cylinder to the proper relative position, the operator must press the same forward.

In the drawings the working-tool is shown in its rearward seated position. When, however, the cylinder has moved rearwardly from the working-tool a short distance, the stop ring will not press on the shoulder 9 of the cylinder, and the cylinder is then free to slide on the socket and be moved forward by the operator to reseat the working-tool since there is a sufficient range of movement provided for this purpose between the handle 6 and the end of the cylinder. This is easily done with the construction shown in the drawings, but when the shank of the working-tool must slide in the socket, the operator is not able to exert sufficient pressure to accomplish this result.

Although a great many devices for rotating the working-tool for rock drills have been proposed, the severe requirements of portable pneumatic hand or unmounted drills has led to the almost universal adoption of a separate lever or wrench which is slipped over the working-tool and held in one hand of the operator. This separate wrench is very inconvenient for the operator, and it is desirable that the means for rotating the working-tool be part of the pneumatic drill. For plug and feather work, the working-tools are dulled quickly and have to be changed often. When the rotating means is held in place, the operator has the free use of both hands for inserting another steel. I prefer the construction shown in Fig. 1 where the socket is retained in the cylinder by the bushing 5, but this is not essential as the socket may be retained in the cylinder by any suitable means as by the spring-clip 8 shown in Fig. 2. It is not essential that the working-tool be rotated through a complete circle in order to drill a round hole. It is not necessary for the proper working of the tool that means shall be provided for automatically retaining the socket within the cylinder; it is simply a matter of convenience for the operator, as when so retained the rotating means does not need his attention to keep it in proper position.

In operation, the working-tool is held to the work by the operator pressing against the handle at the rear end of the tool with one hand. The working-tool is turned forward and back through part of a revolution by means of the handle 6 which is grasped by the other hand of the operator.

In the modification shown in Fig. 3 instead of the employment of a removable stop ring 4, such as shown in Figs. 1 and 2, the socket 3' is extended rearward to engage the shoulder 9 in the forward end of the cyl-

inder, and the rear portion of the socket is formed with tapering sides 4' which serve as a stop for the tapering rear end of the working-tool. This construction is not so desirable on some accounts as the use of the movable stop ring shown in Figs. 1 and 2, because more vibration is imparted to the socket, but such construction I should consider as coming within the scope of my invention.

What I claim is:

1. In a pneumatic impact-tool, a cylinder and piston, a working-tool, a socket in which the shank of the working tool slides easily, said shank being free to move out of reach of the piston when the working-tool is not in contact with the work, and means longitudinally movable with relation to the cylinder adapted to engage the rear end of the working-tool to limit its rearward movement and hold it in alinement with the piston.

2. In a pneumatic impact-tool, a cylinder and piston, a socket at the forward end of the cylinder adapted to receive the shank of a working-tool, said working-tool being free to move out of reach of the piston when not in contact with the work, and means longitudinally movable with relation to the cylinder, adapted to engage the shank of the working-tool adjacent to its rearward end.

3. In a pneumatic impact tool, a cylinder and piston, a socket at the forward end of the cylinder adapted to receive the shank of a working-tool, said working-tool being free to move out of reach of the piston when not in contact with the work, and a stop ring located rearward of said socket adapted to limit the rearward movement of the working tool.

4. In a pneumatic impact tool, a cylinder and piston, a socket at the forward end of the cylinder adapted to receive the shank of a working-tool, said working-tool being free to move out of reach of the piston when not in contact with the work, a stop-ring located rearward of said socket adapted to limit the rearward movement of the working-tool, said stop ring being longitudinally movable and adapted to move the rear end of the working-tool in alinement with the piston.

5. In a pneumatic impact-tool, a cylinder and piston, a socket at the forward end of the cylinder adapted to receive the shank of a working-tool, a working-tool provided with a tapered rear end, said working-tool being free to move out of reach of the piston when not in contact with the work, and a movable stop-ring adapted to engage the tapered end of the working-tool and hold the latter in alinement with the piston.

6. In a pneumatic impact-tool, a cylinder and piston, a socket at the forward end of the cylinder adapted to receive the shank of a working-tool, a working-tool provided with

a tapered rear end, said working-tool being free to move out of reach of the piston when not in contact with the work, and a movable stop-ring adapted to engage the tapered end 5 of the working-tool, said stop-ring being longitudinally movable with relation to the cylinder.

7. In a pneumatic impact-tool, a cylinder and piston, a socket at the forward end of 10 the cylinder adapted to loosely engage the shank of a working-tool, and means at the rear end of the working-tool to limit its rearward movement, said means being free to move out of reach of the piston when the 15 working-tool is not in contact with the work said socket being longitudinally movable with relation to the cylinder and working-tool.

8. In a pneumatic impact-tool, a cylinder 20 and piston, a socket at the forward end of the cylinder adapted to receive the shank of a working-tool, the rear end of the working-tool being tapered, means adapted to engage the tapered end of the working-tool 25 to limit its rearward movement and hold it in alinement with the piston, said means being free to move out of reach of the piston when the working-tool is not in contact with the work and means whereby the working- 30 tool may be rotated.

9. In a pneumatic impact tool, a cylinder and piston, a socket rotatably mounted with relation to the cylinder and adapted to engage the shank of a working-tool, said 35 socket being longitudinally movable with relation to the cylinder and working-tool, said working-tool being free to move out of the socket when not in contact with the work, and means whereby the socket may be 40 moved longitudinally and rotated to rotate the working-tool.

10. In a pneumatic impact-tool, a cylinder and piston, a socket rotatably mounted with relation to the cylinder and adapted to engage the shank of a working-tool, means 45 adapted to engage the rear end of the working-tool to limit its rearward movement, said means being longitudinally movable with relation to the cylinder, and free to move out 50 of reach of the piston when the working-tool is not in contact with the work, and means whereby said socket may be rotated to rotate the working-tool.

11. In a pneumatic impact-tool, a cylinder 55 and piston, a socket rotatably mounted with relation to the cylinder and adapted to engage the shank of a working-tool, means independent of said socket and longitudinally movable with relation thereto adapted to 60 limit the rearward movement of the working-tool and means whereby the socket may be rotated to rotate the working-tool.

12. In a pneumatic impact tool, a cylinder and piston, a socket adapted to receive the

shank of a working-tool, means independent 65 of the piston whereby said socket may be moved forward and rearward with relation to the cylinder and working-tool, and may be rotated to rotate the working-tool.

13. In a pneumatic impact-tool, a cylinder 70 and piston, a socket rotatably mounted with relation to the cylinder and adapted to engage the shank of a working-tool, means independent of the piston whereby said socket may be rotated and may be moved forward 75 and rearward with relation to the cylinder and working-tool, and means to retain the socket in position with relation to the cylinder.

14. In a pneumatic impact-tool, a cylinder 80 and piston, a socket rotatably and longitudinally mounted with relation to the cylinder, means independent of said socket to limit the rearward movement of the working-tool, and means to retain the socket in 85 assembled position with relation to the cylinder.

15. In a pneumatic impact-tool, a cylinder and piston, a socket adapted to receive the shank of a working tool, a working-tool, a 90 stop ring mounted in the cylinder adapted to engage the rear end of the working-tool and limit the rearward movement of the working-tool and hold it in alinement with the piston, said stop ring and working-tool being 95 free to move out of reach of the piston when not in contact with the work, and a bushing in the forward end of the cylinder held in fixed relation thereto and adapted to retain said stop ring and socket in the cylinder. 100

16. In a pneumatic impact tool, a cylinder and piston, a bushing in the forward end of the cylinder held in fixed relation thereto, a 105 socket rotatably and longitudinally movable in the cylinder and retained therein by the said bushing and adapted to engage the working-tool, said working-tool being free to move out of reach of the piston when not in contact with the work, and means whereby 110 said socket may be rotated to rotate the working-tool.

17. In a pneumatic impact tool, a cylinder and piston, a socket adapted to receive the shank of a working-tool, means to limit the 115 rearward movement of the working-tool, said means being free to move out of reach of the piston when the working-tool is not in contact with the work, said socket being longitudinally movable with relation to the cylinder and working-tool, and means whereby 120 the socket may be rotated to rotate the working-tool.

18. In a pneumatic impact-tool, a cylinder and piston, a working-tool receiving direct piston impact, and free to move out of reach 125 of the piston when not in contact with the work, means at the rear end of the working-

tool to limit its rearward movement, said means being longitudinally movable with relation to the cylinder and the working-tool.

19. In a pneumatic impact-tool, a cylinder and piston, a working-tool receiving direct piston impact, means to rotate the working-tool, and means at the rear end of the working-tool to limit its rearward movement, said means being longitudinally movable with relation to the cylinder and the working-tool.

20. In a pneumatic impact tool, a cylinder and piston, a working tool receiving direct piston impact, and a socket in which the shank of the working tool is fitted loosely and 15 is free to move forward with relation to the socket independent of the position of the socket in the cylinder when the working tool is not in contact with the work, the working tool and socket both being longitudinally 20 movable with relation to the cylinder.

21. In a pneumatic impact tool, a cylinder and piston, a working tool receiving direct piston impact, and a socket in which the shank of the working tool is fitted loosely and 25 is free to move forward with relation to the socket independent of the position of the socket in the cylinder when the working tool is not in contact with the work, the working tool and cylinder both being longitudinally 30 movable with relation to the socket.

22. In a pneumatic impact-tool, a cylinder and piston, a working-tool, an intermediate member between the cylinder and working-tool adapted to limit the rearward movement of the latter, the working-tool being normally free to move forward out of reach 35 of the piston when not in contact with the work, said member being longitudinally movable with relation to the cylinder.

40 23. In a pneumatic impact-tool, a cylinder and piston, a working-tool, an intermediate member between the cylinder and working-tool adapted to loosely engage the rear end of the working-tool, the latter being normally free to move forward out of reach of the piston when not in contact with the work, said intermediate member being longitudinally 45 movable and means to limit the longitudinal movement of said intermediate member with relation to the cylinder.

24. In a pneumatic impact-tool, a cylinder and piston, a working-tool, an intermediate member between the cylinder and working-tool longitudinally movable with relation to the 55 cylinder and adapted to form a seat for the rear end of the working-tool, the latter being normally free to move forward out of reach of the piston when not in contact with the work and a shoulder on the cylinder 60 which forms a stop for said intermediate member when the latter is in its rearward position.

25. In a pneumatic impact-tool, a cylinder and piston, a working tool free to move out

of reach of the piston when not in contact 65 with the work, an intermediate member between the cylinder and working-tool adapted to limit the rearward movement of the latter, said intermediate member being longitudinally movable with relation to the cylinder 70 and free to rotate with relation to the working-tool.

26. In a pneumatic impact-tool, a cylinder and piston, a working-tool free to move out of reach of the piston when not in contact 75 with the work, an intermediate member between the cylinder and working-tool adapted to limit the rearward movement of the latter, said intermediate member being longitudinally movable with relation to the cylinder 80 and free to rotate with relation to the working-tool, a bushing in the forward end of the cylinder held in fixed relation thereto and adapted to retain said intermediate member in assembled position.

27. In a pneumatic impact-tool, a cylinder and piston, a working-tool free to move out of reach of the piston when not in contact with the work, a socket longitudinally movable with relation to the cylinder adapted to 90 loosely engage the shank of the working-tool, a bushing in the forward end of the cylinder held in fixed relation thereto, and adapted to retain said socket in assembled position, and means rearward of said socket adapted to 95 limit the rearward movement of the working-tool.

28. In a pneumatic impact-tool, a cylinder and piston, a working-tool receiving direct piston impact and free to move out of reach 100 of the piston when not in contact with the work, means adapted to engage the rear end of the working-tool to limit its rearward movement, said means being longitudinally 105 movable with relation to the working-tool and cylinder.

29. In a pneumatic impact-tool, a cylinder and piston, a working-tool receiving direct piston impact and free to move out of reach 110 of the piston when not in contact with the work, means adapted to engage the rear end of the working-tool to limit its rearward movement, said means being longitudinally 115 movable with relation to the working-tool and rotatably movable with relation to the cylinder.

30. In a pneumatic impact-tool, a cylinder and piston, a working-tool receiving direct piston impact and free to move out of reach 120 of the piston when not in contact with the work, a socket adapted to engage the shank of the working-tool and limit its rearward movement, said shank being longitudinally 125 movable in the socket, and said socket being longitudinally movable with relation to the cylinder.

31. In a pneumatic impact-tool, a cylinder and piston, a working-tool receiving

direct piston impact, a socket and means adapted to engage the shank of the working-tool and limit its rearward movement, said shank being longitudinally movable in the 5 socket, said socket being longitudinally and rotatably mounted with relation to the cylinder and means whereby the socket may be rotated to rotate the working-tool.

32. In a pneumatic impact-tool, a cylinder and piston, a working - tool, a socket longitudinally movable with relation to the cylinder and means adapted to loosely engage the shank of the working-tool and limit its rearward movement, said working-tool 15 being normally free to move forward with relation to the socket and means to retain said socket in assembled position with relation to the cylinder.

33. In a pneumatic impact-tool, a cylinder and piston, a socket at the forward end of the cylinder, a working - tool receiving direct piston impact, means adapted to engage the rear end of the working-tool to limit its rearward movement, said means 20 25 being longitudinally and rotatably movable with relation to the working-tool and cylinder, and free to move out of reach of the

piston when the working-tool is not in contact with the work.

34. In a pneumatic impact-tool, a cylinder and piston, a socket at the forward end of the cylinder, a working-tool receiving direct piston impact, means adapted to engage the rear end of the working-tool to limit its rearward movement, said means 30 35 being longitudinally movable with relation to the cylinder and free to move out of reach of the piston when the working-tool is not in contact with the work.

35. In a pneumatic impact-tool, a cylinder and piston, a socket at the forward end of the cylinder, a working - tool, means adapted to receive the shank of the working-tool and limit its rearward movement, said means being longitudinally movable with 40 45 relation to the cylinder and free to move out of reach of the piston when the working-tool is not in contact with the work.

In testimony whereof I affix my signature, in presence of two witnesses.

GEORGE L. BADGER.
